Patented Sept. 19, 1916.

UNITED STATES PATENT OFFICE.

GEORGE G. PERKINS, OF LYNN, MASSACHUSETTS.

LAST.

1,198,868.

Specification of Letters Patent. Patented Sept. 19, 1916.

Application filed June 15, 1914. Serial No. 845,098.

To all whom it may concern:

Be it known that I, GEORGE G. PERKINS, a citizen of the United States, and a resident of Lynn, in the county of Essex and 5 State of Massachusetts, have invented a new and useful Improvement in Lasts, of which the following is a specification.

The present invention relates to hinged lasts for shoes and its object is to provide 10 a simple device of this character that may be shortened for the purpose of ready removal from a shoe and firmly locked in lengthened position when in use.

An illustrative embodiment of my invention is shown in the drawing which accompanies and forms a part of this specification; the figure being a central longitudinal section of my improved last.

In the particular drawing selected for 20 more fully disclosing the principle of my invention, 1 represents the toe portion and 2 the heel portion of the last, these two portions being provided with longitudinally-extending slots or recesses 3 3', respectively, said recesses being in alinement the one with the other. A link 4 disposed in the alined recesses and pivoted to the toe portion by the pin 5 and also, in the present instance, to the heel portion by the pin 5', 25 serves as a hinge portion whereby the toe member may be rotated to the position shown in dotted lines about the pin 5 as a center and also, in the example shown in the drawing, to a limited extent about the pin 5' for the purpose of shortening the 30 length of the last to permit its ready removal from the shoe. The abutting faces of the heel and toe portions preferably are arc-shaped as shown at 6 6', said arcs being 35 struck from the center of the pin 5. A straight portion 6'' connects the two arc-shaped portions above referred to and limits the movement of the heel portion with respect to the toe portion when the last is in 40 operative or lengthened position.

For locking the two portions in operative position, I employ the detent or locking piece 7 located in the recess 3 of the toe portion and pivoted to said portion by the pin 50 8. The lower end of said detent is forced into contact with the upper edge of the link 4 by the resilient member 9 herein shown as a spiral spring disposed in the bore 10 and having its upper end in contact with and 55 partially surrounding the rounded upper projection 11 of the detent 7. Opposite said

projection 11 is a finger piece 12, which projects into the substantially V-shaped space between the heel and toe portions. At the point where the lower end of the detent 60 bears upon the upper edge of the link 4, I prefer to shape the surface of contact as shown at 13, 13', the straight portion 13 being tangential to the curved portion 13' and lying below the arc *a*, the center of which 65 is the center of the pin 8 and which has a radius *b*, and the curved portion 13', which is forward of the normal point of contact between the detent and link, lying above the arc *a*. The object of so shaping the surfaces 13, 13' is to permit of a certain amount of wear of the contact surfaces without impairing the effectiveness of the lock. 70

It will be readily apparent that the locking device above described will maintain the 75 last in its lengthened position during the process of lasting, and that by rotating the finger-piece 12 about its center, the heel-piece may be unlocked and the last shortened as shown in dotted lines thereby materially 80 decreasing the length of the same and permitting its ready removal from the shoe. The point of pivotal connection of the link 4 with the toe-piece is approximately midway between the ends of said piece, so that 85 the arc through which any point on the rear of the heel-piece will swing has a radius equal approximately to one-half the total length of the last when in operative position. It will be noted that the pivot 90 5 connecting the link with the toe-portion is below the base line or the heel-line of the last, *i. e.*, a line passing along the bottom of the heel and extended forwardly. This permits the last to be progressively or 95 continuously shortened from the very beginning of the pivotal movement of the heel-piece without the slightest tendency to lengthen during the first part of the movement and afterward shorten, and thereby 100 the heel-lining of the shoe from which the last is being withdrawn, is protected from injury which otherwise would result from such withdrawal. It will be further noted that the toe-piece and heel-piece each has a 105 solid bottom, the kerfs or recesses not extending therethrough, and this is of advantage in that the last is thereby materially strengthened, and openings in which nails, &c., are liable to be caught, are eliminated. 110

Having thus described an illustrative embodiment of my invention, what I claim

as new and desire to secure by Letters Patent, is—

1. In a last, the combination with a toe-piece, a heel-piece and a link connecting said pieces, of a detent pivoted to one of said pieces and arranged to coöperate with said link, said link having a straight upper edge at the point where the lower end of said detent makes contact therewith, said 10 upper edge having a curved portion immediately forward of the normal point of contact between said detent and link.

2. In a last, the combination with a toe-piece, a heel-piece and a link connecting said pieces, of a detent pivoted to one of said pieces and arranged to coöperate with said link, the upper edge of said link having a straight portion and a forwardly-extending curved portion, said straight portion at 20 the point of contact of said detent therewith being tangential to said forwardly-extending curved portion, said curved portion lying above the arc whose radius is equal to the distance between the center of 25 the pivot of said detent and the lower end thereof.

3. In a last, the combination with a toe-piece, a heel-piece and a link connecting said pieces, of a detent pivoted to one of said pieces and arranged to coöperate with said link, said link having a straight upper 30 edge at the point where the lower end of

said detent makes contact therewith, said upper edge having a curved portion immediately forward of the normal point of contact between said detent and link, and resilient means engaging said detent to normally maintain the same in engagement with said link to lock the last in lengthened position. 35

4. In a last, the combination with a toe-piece, a heel-piece and a link connecting said pieces, of a detent pivoted to one of said pieces and arranged to coöperate with said link, the upper edge of said link having a straight portion and a forwardly-extending curved portion, said straight portion at 40 the point of contact of said detent therewith being tangential to said forwardly-extending curved portion, said curved portion lying above the arc whose radius is equal to the distance between the center of the pivot of said detent and the lower end thereof, and resilient means engaging said detent to normally maintain 45 the same in engagement with said link to lock the last in lengthened position. 50

In testimony whereof, I have hereunto subscribed my name this 12 day of June, 1914.

GEORGE G. PERKINS.
